ORWELL H. NEEDHAM, OF NEW YORK, N. Y.

Letters Patent No. 82,629, dated September 29, 1868.

IMPROVEMENT IN ATMOSPHERIC KNOB.

The Schedule referred to in these Letters Patent and making part of the same.

TO ALL WHOM IT MAY CONCERN:

Be it known that I, ORWELL H. NEEDHAM, of the city, county, and State of New York, have invented a new and useful Improvement in Atmospheric Knobs or Handles, of which the following is a full, clear, and exact description, reference being had to the accompanying drawing, forming part of this specification, and in which—

Figure 1 represents a side view of a knob or handle constructed in accordance with my improvement.

Figure 2, a transverse section of the same, prior to its compression to produce the necessary suction or hold on the drawer or surface to which it is designed to apply the knob; and

Figure 3 a similar view of the same, as compressed to establish the gripe or suction.

Similar letters of reference indicate corresponding parts.

My invention consists in the production of an atmospheric knob or handle, applicable to opening drawers or doors, and other purposes, in which not only the suction or holding-plate or face of the handle is made of rubber or other suitable flexible or elastic material, but in which the knob portion of the handle, that may be made out of the same piece with the face or sucker portion, is also flexible or elastic, and formed with a cavity inside of it, in communication, by passage, with the inner face of the sucker portion, so that on applying the handle to the drawer, or other object it is designed to take hold of, a vacuum may be produced on the inside of the handle, not merely by flattening or compressing the sucker portion, and afterwards relieving the same of such force or pressure, but also by compressing the hollow knob portion of the handle, and allowing such flexible part to spring back or out.

Referring to the accompanying drawing, A represents the suction-plate or face portion of the handle, and B the knob part thereof, made in one piece of rubber, or other flexible or elastic and air-tight material.

The sucker or face portion, A, of the handle should be more or less curved or cupped, so as to constitute a hollow, *a*, and the knob part, B, of the handle made hollow, or with a cavity, *b*, between which and the space *a*, a contracted passage, *c*, is arranged to establish communication, said passage being formed in or through a separate plug-piece, C, cemented within the handle, and which gives a body-like or stiff character to the neck of the latter.

To use the handle, it is only necessary, in pressing it up or against the drawer or other object, as represented in fig. 3, to at the same time expel the air from the cavity *b*, by pressing in or down the flexible hollow knob part, which afterwards, in recovering its usual shape or figure, by reason of its elasticity, induces suction, and so assists to perfect the vacuum or rarefaction on the inside face of the sucker portion of the handle, and to extend, as it were, the area of the same.

In this way, or by such construction, the atmospheric pressure on the back or outside of the handle is increased, and the adhering or pulling capacity of the handle enlarged on applying draught to the handle through its knob, which, in being connected in a comparatively solid manner through its neck with the sucker portion, admits of a strong direct pull without destroying the figure of the handle. The contracted passage *c* also insures a longer hold of the handle on the object to which it is applied, by reason of the slow ingress it establishes for air leaking past the sucker portion, A, to the enlarged cavity, *b*, of the knob or knob part B, that, by its capacity and flexibility, thus prolongs, in springing back, its exhausting action on the sucking portion A.

By making the knob and face-holding and sucking portions of the handle in one piece, there is not only saving of labor and expense, but less liability to leakage.

For opening doors or drawers to which the regular handles have been lost, or from which they have become detached, this device will be found exceedingly handy or convenient, besides which there are many other purposes to which such a portable or removable handle may be applied.

What is here claimed, and desired to be secured by Letters Patent, is—

An atmospheric handle, composed of a flexible face or sucker portion A, and flexible or elastic knob or knob-part B, having a cavity, *b*, within it in communication, by a passage, *c*, with the interior face of the sucker portion or space contained therein, substantially as specified.

ORWELL H. NEEDHAM.
